MAGAZINE NAIL HAMMER

James Eller, Lee Eller, and Frank J. Youmans,
Wheat Ridge, Colo.

Application May 10, 1933, Serial No. 670,350

4 Claims. (Cl. 1-45)

The present invention relates to a hammer and more specifically to an automatic hammer in which the nails are automatically fed to a nailing position.

One of the objects of the present invention is to provide a hatchet or hammer equipped with a nail feeding device which may be actuated by the user to automatically feed a nail to nailing position thereby eliminating the necessity of using both hands, to the end that one hand may be free to be used in any desired position.

Another important object of the invention is to construct an automatic nail feeding hammer which is positive in its operation, cheap to manufacture and simple to operate.

The present invention broadly contemplates the provision of a hammer having a specially constructed hollow nail receiving and feeding handle, and a cylindrical trigger actuated nail feeding magazine for automatically feeding the nails to a magnetic head which maintains them in a position for effecting the nailing thereof.

In the accompanying drawings forming a part of this application in which corresponding parts are designated by similar reference numerals,

Figure 1 is a front elevational view of the hammer partly in section.

Figure 2 is a top plan view of Figure 1 partly broken away.

Figure 3 is an enlarged fragmentary view partly in section.

Figure 4 is a bottom plan view of Figure 3.

Figure 5 is a vertical sectional view of Figure 1 taken on line 5-5 thereof.

Figure 6 is a perspective view of the nail feeding mechanism illustrating the manner in which it is slidable in the removable lid of the hammer, a portion of the hammer lid being shown.

Figure 7 is a modified form of the invention showing the trigger mechanism arranged in the top portion of the handle of the hammer, and a removable magnetic member in the head of the hammer.

In the accompanying drawings, wherein for the purpose of illustration there is shown preferred embodiments of the invention, and referring more particularly to Figures 1 to 6, inclusive, the reference numeral 8 generally designates the head of the hammer, which in the present form is illustrated as a hatchet head. The head 8 is provided with the usual hammering portion 10 which as illustrated is serrated, and is provided in the rear portion thereof with a vertical nail receiving pocket 12. The head is provided with an integral hollow handle 14 with a removable lid 16.

Within the handle portion 14, and the adjacent head 10 there is rotatably mounted a cylindrical magazine 18. As clearly illustrated the magazine 18 is rotatably mounted within the handle on the spindle 20 the upper end of which extends into an aperture in the wall of the handle, the cylinder being held in position by means of the screw-threaded plug 22 into which in an aperture therein extends the lower pin 24. The cylinder 18 is provided with a plurality of spaced longitudinally extending nail receiving slots 26.

In the tubular handle 14 there is arranged a nail receiving magazine 28 which is provided with a plurality of spaced vertical longitudinally extending nail receiving slots 30 and as clearly illustrated the upper portion of the magazine terminates short of the inner side of the handle to permit of the passage of the heads of the nails through the nail receiving slot in the handle.

The nail receiving pocket 12 in the magnetized hammer head 10 is in communication with the rotatably mounted magazine 18 through the medium of the longitudinally extending slot 34. On the bottom of the rotatably mounted magazine 18 there is provided a ratchet wheel 36 actuated by means of the trigger rod 40 which is slidably disposed in a groove in one side of the handle 14. The ratchet wheel is prevented from freely rotating by a resiliently mounted pawl 44 secured to one side of the handle. One end of the trigger rod 40 is pointed and adapted to engage as clearly illustrated in Figure 4 the ratchet wheel and the other end thereof extends upward through an opening or aperture in the slot of the handle defining a trigger. The trigger rod 40 is normally maintained in and out of engagement position with respect to the ratchet wheel 36 by means of the spring 46 coiled thereabout. It will thus be seen that upon actuation of the trigger 48 the trigger rod 40 is pushed into engagement with one of the cogs of the ratchet wheel 36 causing intermittent rotation thereof to present one of the vertical slots into registry engagement with the longitudinally extending slot 34 to the end that the magnetic attraction of the head 10 pulls the nail from the magazine through the slot 34 into the nail receiving pocket 12 whereupon receiving a light blow the same will remain or stick in the material and upon the application of repeated blows on the head 10 can be driven therein.

As clearly illustrated the forward end of the nail receiving magazine 28 is of arcuate shape and is disposed adjacent the cylindrical magazine 18. The nails are fed from the longitudinally

extending slot 30 in the magazine 28 to the slot in the rotatable magazine by means of a gate 52 which is slidable in a longitudinally extending slot 54 in the cover. It is to be noted that the 5 gate which is slidable beneath the magazine and the underneath side of the cover 16 is of inverted U-shape and has spacedly downwardly extending arms 56, the terminal ends of which are upturned as clearly illustrated. The inverted U-shaped cross member 58 is provided at its mid-point with a threaded aperture into which there is screw-threaded the set screw 60 which slides in the longitudinally extending guideway or slot 54 in the handle. The gate may be fixedly secured at predetermined position through the medium of the adjusting nut 64. The nail receiving magazine 28 is held in the handle by means of the cap 68 which is resiliently secured thereto by means of the spring 70. Obviously upon an 10 advancement of the gate, or a hammering movement of the hammer the nails in the longitudinally extending slots will be moved forwardly and pass down the inclined guideways into the vertical slots of the cylinder which register with the 15 slot 30 for subsequent movement upon actuation of the trigger 48 to a nailing position. It is to be noted in this connection that the head of the hammer is constructed of a hard material to the end that the frequent hammering and contacting therewith will not cause the same to lose its 20 magnetic properties, as would be the case if the same were constructed of a soft material.

Referring now more particularly to Figure 7 illustrating a modified form of the invention it 25 will be seen that the hammer is substantially the same as that illustrated in the previous figure with the exception that the actuating rod or trigger is in the form of a push lever 76 disposed above the nail magazine 28. One end extends 30 through an aperture in the handle and is slightly curved as illustrated defining an actuating trigger 78 to be actuated by pushing the same forward with the thumb. The other end of the actuating rod 76 is provided with a ratchet 80 35 which cooperates with the teeth on the cog wheel 82. The push rod 76 is normally maintained in its out-of-engagement position by means of the coil spring 84 disposed in the pocket in the handle and surrounding the rod. As clearly illustrated, 40 the forward end of the spring abuts one side of the pocket and the other end normally engages a stop 88 secured to the push rod 76. It will thus be seen that upon the forward pushing of the rod 76 the ratchet of the rod engages the cog wheel 45 82 to intermittently rotate the rotatable magazine 90 of the same construction as the magazine previously described in the other figure to present one of the slots containing a nail in registering engagement with the groove 96. The 50 nails fall through the slot 96 by means of the magnet 100 secured in a pocket in the head of the hammer. The magnet 100 has a circumferentially extending groove in the upper end thereof into which there is received a set screw 102 extending transversely in the hammer for securing the magnet 100 therein. The magnet 100 is provided with a nail receiving pocket similar to the 55 pocket previously described in the other figures to the end, that the magnetic attraction of the magnet 100 causes the nails to be pulled into the nail receiving pocket from the slot 96.

While there is shown for the purpose of illustration only preferred embodiments of the invention, it is to be understood that it is capable 60 of various changes and modifications without

departing from the spirit thereof, and it is intended, therefore, that only such limitations shall be imposed thereon as are indicated in the prior art or in the appended claims.

Having thus described the invention what is 65 claimed is:

1. In a hatchet having a hollow handle and a hammering head, a nail magazine therein having spaced longitudinally extending nail receiving grooves, a rotatably mounted cylindrical 10 magazine in said handle adjacent said head having spaced nail receiving grooves therein and adapted upon rotation thereof to register with the longitudinally extending nail receiving grooves, said hammering head being magnetized 15 and having a nail receiving pocket therein, said handle having a longitudinally extending slot communicating the grooves of said cylindrical magazine with said nail receiving pocket, and means for intermittently rotating said cylindrical 20 magazine to effect a registering of the nail receiving grooves of the cylinder with the slot whereby a nail may be selectively brought into nailing position in the pocket of said magnetic head. 25

2. In a device of the class described having a hollow handle and a magnetized hammering head, a nail magazine in the hollow handle having spaced longitudinally extending nail receiving grooves therein, a rotatably mounted cylindrical magazine in said handle disposed adjacent said head having nail receiving grooves 30 therein adapted upon rotation of the magazine to register with the longitudinally extending grooves in the magazine in the handle, said magnetic head being provided with a vertically extending nail receiving pocket, a slot communicating the pocket with the nail receiving slots in the cylindrical magazine, a ratchet wheel on one end of said cylindrical magazine, a pawl for 35 normally maintaining said cylindrical magazine in position, and a trigger mechanism engaging the cogs of said ratchet wheel for intermittently actuating the same to effect the intermittent registering of the longitudinally extending nail 40 receiving grooves in the magazine with the slot communicating with the nail receiving pocket in the hammer and the longitudinally extending grooves in the magazine in the handle. 45

3. In a hatchet having a hollow handle and 50 a hammer head, a nail magazine therein having a longitudinally extending nail receiving groove, a rotatably mounted cylindrical magazine in said handle adjacent said head having spaced nail receiving grooves therein adapted upon rotation 55 thereof to register with the longitudinally extending nail receiving groove, said hammer head including a magnetized portion and having a nail receiving pocket therein, said handle having a longitudinally extending slot communicating the 60 grooves of said cylindrical magazine with said nail receiving pocket, and means for intermittently rotating said cylindrical magazine to effect a registering of the nail receiving grooves of the cylindrical magazine with the slot whereby a 65 nail may be selectively brought into nailing position in the pocket of the hammering head.

4. In a hatchet having a hollow handle and a hammer head, a nail magazine having a longitudinally extending nail receiving groove therein, a rotatably mounted cylindrical magazine in said handle adjacent said head having spaced nail receiving grooves therein adapted upon rotation thereof to register with the longitudinally extending nail receiving groove, said hammer 70 75

head being magnetized and having a nail receiving pocket therein, said handle having a longitudinally extending slot communicating the grooves of said cylindrical magazine with said nail receiving pocket, and means for intermittently rotating said cylindrical magazine to effect a registering of the nail receiving grooves

of the cylinder with the slot whereby a nail may be selectively brought into nailing position in the pocket of said magnetic head.
